VENTILATING HEATER FOR AUTOMOBILES

Robert F. Ostrander, New Haven, Conn.

Application August 8, 1935, Serial No. 35,294

5 Claims. (Cl. 98—2)

This invention relates to interior heaters for motor vehicles, and pertains more particularly to a ventilating heater for circulating warm air within the body of an automobile.

5 The commercial auto heaters heretofore in common use have comprised either a jacket or housing mounted upon the exhaust pipe of the motor and provided with a conduit leading to the interior of the car body for conveying heated 10 air thereto, or a small radiator located inside the body and connected to the water system of the motor and provided with an electrically driven fan for forcing heat into the interior of the car. Each of these types of heaters are unsatisfactory 15 under varying weather conditions because of the objectionable features inherent in its construction and operation.

In the hot air or exhaust type, the air admitted to the car is necessarily taken from the motor 20 compartment and is consequently contaminated by the dirt, monoxide gas and other fumes of the motor; the temperature of the heated air is uncontrollable, and the attempt to regulate the quantity by dampers or shutters is unsatisfactory; 25 and the entire installation must be removed in summer.

In the fan-type radiator, dead air within the car body is continuously recirculated by the electrically driven fan; the fan causes a serious drain 30 on the car battery, especially when the fan motor is left running while the car motor is idle; the fan and motor and the inefficient shutters are noisy; the heated air is directed rearwardly as a blast or stream and tends to create drafts because of the wide temperature ranges within the 35 car body; and the installation occupies a substantial space, usually interfering with the "leg room" of a passenger on the front seat.

The purpose of the present invention is to improve car heaters by eliminating these objectionable features of the former installations, and by providing simple and efficient apparatus which will not only furnish the desired amount of controlled heat for the comfort of the driver and his 45 passengers, but which will also ensure a continuous supply of warmed fresh air to the interior of the car, without creating drafts or introducing dirt, moisture or gasoline fumes within the car body.

50 The specific features of the improved apparatus and their attendant advantages will be apparent from the following description of a recommended embodiment of the invention illustrated in the accompanying drawing, and will be pointed 55 out in the appended claims. It will be under-

stood, however, that the structural details of the installation may be varied to suit special circumstances without departing from the spirit of my invention.

In the drawing.

Fig. 1 is a diagrammatic representation, partly in elevation and partly in section, of the front portion of a passenger automobile equipped with the improved ventilating heater;

Fig. 2 is an enlarged section taken on line 2—2 of Fig. 1;

Fig. 3 is an enlarged elevation, partly broken away, of a radiator unit forming part of the installation; and

Fig. 4 is an enlarged section on line 4—4 of Fig. 2.

In the particular embodiment chosen for the purpose of illustration, the combined heating and ventilating apparatus is installed in a typical coach or sedan type automobile having a cowl 20 ventilator or shutter 11 pivoted in any usual manner in the cowl 12, and provided with an operating lever 13 which bears against an arm 14 so that the ventilator may be held in regulated position by the engagement of the arm within 25 spaced notches on an arcuate portion of the lever. The ventilator usually has a screen 15 which prevents the admission of dirt or other foreign substances through the ventilating opening.

The car also has the usual dash board 16 and 30 instrument panel 17 as integral parts of its forward compartment, as well as the motor block 18, front radiator 19, hose connections 20 and 21, and water pump 22 constituting the cooling system for the motor.

35 My improved apparatus preferably comprises a heating unit indicated generally at 23 in Fig. 1, hose connections or conduits 24 and 25 leading to the lines 20 and 21 respectively of the motor cooling system, and a housing or base member 26 40 for supporting the radiator unit 23 so that all air admitted through the cowl ventilator is circulated through its coils and then passes outwardly or downwardly of said housing and is diffused, as warmed fresh air, throughout the interior of the 45 car body. One of the windows of the car should be opened slightly, as indicated at 27 (Fig. 1), to provide an outlet for spent air and to insure continuous circulation of fresh air within the car.

The heating unit 23 preferably consists of a 50 tubular, honeycomb type core or radiator section such as is commonly employed for the front radiator 19, and a pair of end members or headers 28 and 29 secured over the ends of the radiator tubes 30 (Fig. 3) to ensure proper water circu- 55

lation therethrough. The respective headers have unions 31 and 32 to which the hoses 24 and 25 are connected. The size of the unit may vary according to the make and model of the automobile, but a section 3½ inches deep, 5 inches wide and 24 inches long will fit comfortably behind the instrument panel of most cars and will afford ample heating capacity, approximately seven times the radiation provided by the ordinary fan type heaters, without obstructing the space needed by occupants.

The housing 26 preferably consists of moisture-absorbent sheet material, for example fibrous wall board, of sufficient thickness to support the radiator unit, to insulate the heating compartment, and to absorb moisture from the air entering through the ventilator 11. This board or base member is suitably mounted between the dashboard 16 and instrument panel 17 and extends from side to side of the car, thus completely enclosing the space beneath the ventilator, except for the opening 33 immediately below the radiator unit 23 through which the warmed air passes to the interior of the car.

The housing may also have a narrow slot 34 which receives the ventilator lever 13, and this opening may be efficiently sealed by strips of yielding material such as sponge rubber 35 which embrace the arm of the lever while permitting movement thereof to open or close the ventilator, as shown in Fig. 4.

The hot water conduit or hose 24 leads from the outlet of the water manifold of the motor (where the water temperature is highest) to the intake 31 of the radiator section, which is preferably located at the bottom of the header 28. The connection 36 to hose 20 preferably includes a well known type of spring actuated thermostat (not shown) regulated to a temperature of approximately 160° F., so that hot water will be continuously supplied to the heater at a substantially constant temperature. A valve 37, located in the inlet hose and having a handle or knob disposed beneath the base member 26, is preferably provided adjacent the intake union 31, so that the heater may readily be regulated or completely shut off by the operator whenever it is not needed to warm the car.

The return conduit or hose 25 leads from the outlet connection 32, preferably leading from the top of the header 29, to the return hose 21 of the front radiator, ahead of the pump 22. While the heater is in operation, the water will freely circulate through the radiator unit and its hose connections owing to the action of the pump 22 and the connection currents in the motor heating system.

By locating the hot water inlet 31 at the bottom of the heating unit and the outlet 32 at the top of its opposite end, complete expulsion of any air in the headers or tubes of the core is assured upon filling the radiator unit with hot water, so that the entire capacity of the core is utilized for heating while avoiding any dead air pockets. Furthermore, this arrangement usually permits the water in the heating unit to flow off through the inlet hose 24 when the motor cooling system is drained. If, however, the inlet hose should, at any point, be directed above the level of the post 31, an auxiliary drain vent 38 (Fig. 3) may be provided at the bottom of one of the headers.

It will be apparent from the foregoing that my improved ventilating heater is easy and economical to install, unusually compact in con-

struction, and out of sight as well as out of the way (behind the instrument panel) so that it is not necessary to remove the installation during the summer months; that warmed fresh air is continuously circulated through the car at a substantially constant, controllable temperature, free from drafts or obnoxious fumes; that the system is noiseless and economical because of the elimination of movable shutters, fans and operating motors therefor; and that the comfort of the occupants of the car is assured regardless of the temperature outside the car. It has been demonstrated that the temperature within the car may be regulated by adjusting the opening of the ventilator 11 or by turning the control valve 37; it may also be varied by changing the size of the window opening 27, for experience has shown that a wider opening (up to a distance of three or four inches) increases the circulation of the fresh air entering through the ventilator and thus causes more warm air to flow through the interior of the car, without admitting an appreciable amount of cold air through the opened window; whereas, a narrower opening will reduce the circulation of air through the heating unit, and consequently lower the temperature within the car. Obviously, the temperature is reduced when the ventilator 11 is closed; and the heating unit ceases to function when the valve 37 is shut off.

It will be found that the air leaving the heating unit 23 through the housing opening 33 spreads throughout the entire interior of the car body to such an extent that a passenger unfamiliar with the concealed apparatus has difficulty in predicting the source of the heat, inasmuch as there is no directed stream of hot air such as is produced by a fan. All the occupants of the car are comfortably warmed by the improved heating apparatus as soon as the car is put in motion; and the radiator will serve to keep the car warm for a reasonable period after it has been stopped, especially if the motor is left running.

As the radiator unit is substantially smaller than the heater chamber in which it is located, fresh cold air entering the chamber through the ventilating opening will circulate through the compartment and receive a preliminary warming before it enters the radiator core; and any excessive moisture will be absorbed by the inner surface of the absorbent sheet which constitutes the housing member or base of said chamber.

I claim:

1. In a motor vehicle having an enclosed body, a heater chamber constructed within the vehicle body and including a housing member, a heating unit substantially smaller than said chamber located therein and mounted against said housing, one wall of the chamber having a ventilating opening for admitting fresh air thereto, said housing having an opening communicating with the heating unit for distributing warmed air to the interior of the body, the vehicle body having a window arranged to be opened to cause circulation of fresh air through the heater chamber and the interior of the body, and said housing member consisting of a sheet of absorbent material adapted to absorb moisture admitted to the heater chamber through said ventilating opening.

2. In a motor vehicle having a closed body provided with a dashboard and an instrument panel, a housing member bridging the space between said dashboard and panel and providing a heater chamber, a heating unit substantially smaller

- than said chamber located therein and mounted on said housing member, one wall of the chamber having a ventilating opening for admitting fresh air thereto, said housing having an opening communicating with the heating unit for distributing warmed air to the interior of the body, the vehicle body having a window arranged to be opened to cause circulation of fresh air through the heater chamber and the interior of the body.
- 5 3. In a motor vehicle having a closed body provided with a dashboard and an instrument panel, a housing member bridging the space between said dashboard and panel and providing a heater chamber, a heating unit substantially smaller than said chamber located therein and mounted on said housing member, the top wall of the chamber having a ventilating opening for admitting fresh air thereto, said housing having an opening located beneath the heating unit for distributing warmed air to the interior of the body, the vehicle body having a window arranged to be opened to cause circulation of fresh air through the heater chamber and the interior of the body, and said housing member consisting of a sheet of absorbent material adapted to absorb moisture admitted to the heater chamber through said ventilating opening.
- 10 4. In a motor vehicle having a closed body provided with a cowl, dashboard and instrument panel, a base member bridging the space between said dashboard and panel and extending substantially from side to side of the body to provide a heater chamber under said cowl and behind said panel, a radiator section substantially smaller in size than said chamber mounted on said base member, an adjustable ventilator in said cowl for admitting fresh air to the chamber, the base member having an opening immediately beneath said radiator section for distributing warmed air to the interior of the body, the radiator section having enclosing headers on its opposite ends, the vehicle body having a window arranged to be opened to cause circulation of fresh air through the heater chamber and the interior of the body.
- 15 5. In a motor vehicle having a closed body provided with a cowl, dashboard and instrument panel, a base member bridging the space between said dashboard and panel and extending from side to side of the body to provide a heater chamber under said cowl and behind said panel, a radiator section substantially smaller in size than said chamber mounted on said base member, an adjustable ventilator in said cowl for admitting fresh air to the chamber, the base member having an opening immediately beneath said radiator section for distributing warmed air to the interior of the body, the radiator section having enclosing headers on its opposite ends, the vehicle body having a window arranged to be opened to cause circulation of fresh air through the heater chamber and the interior of the body, and said base member consisting of a sheet of fibrous absorbent material adapted to absorb moisture admitted to the chamber through the cowl ventilator.
